CLAIM

The ornamental design for the squeegee handle, as shown and described.

DESCRIPTION

FIG. 1 is a perspective view of a squeegee handle of this invention as viewed from the bottom, rear, and side, a replaceable blade member not forming a part of the design being shown in broken lines.

FIG. 2 is a perspective view of the top front of the squeegee handle of FIG. 1; and,

FIG. 3 is a right side elevation view of FIG. 2, the left side being a mirror image.
